UNITED STATES PATENT OFFICE.

FRANK S. CLARKSON, OF BALTIMORE, MARYLAND, ASSIGNOR TO FRANK B. SLOAN, OF SAME PLACE.

FRICITION-HINGE.

SPECIFICATION forming part of Letters Patent No. 290,398, dated December 18, 1883.

Application filed January 24, 1883. (No model.)

To all whom it may concern:

Be it known that I, FRANK S. CLARKSON, a citizen of the United States, residing at Baltimore, Maryland, have invented certain new and useful Improvements in Friction-Hinges, of which the following is a specification, reference being had to the accompanying drawings, forming part hereof, in which—

Figure 1 is a perspective view of my invention, partly broken away. Fig. 2 is a longitudinal central section of the same.

Like letters of reference are applied to the same parts in both figures.

Referring to the drawings by letter, A represents one leaf, and B the other. The leaf A is provided with a pintle, *a*, and the leaf B with a socket, *b*.

The pintle *a*, which enters and turns in the socket *b*, is of a smaller diameter than the socket, and is bent as shown, so that it will be necessary to exert some force in inserting it in the socket.

It will be seen that the pintle has two bearings on one side of the socket, as at *c d*, and one on the opposite side, as at *e*.

The friction of the pintle in the socket will be sufficient to resist a considerable effort to move the leaves, thus serving to hold the leaves firmly at any angle desired.

The simplicity and effectiveness of my device will be apparent at a glance.

I am aware that a friction-hinge with split pintle is old, and consequently do not claim such construction.

Having thus fully described my invention, what I claim, and desire to secure by Letters Patent, is—

The combination of leaf A, pintle *a*, and leaf B, having socket *b*, the pintle *a* being bent, as described, whereby bearings *c d* are provided, for the purpose set forth.

In witness whereof I have subscribed my name.

FRANK S. CLARKSON.
